UNITED STATES PATENT OFFICE.

CHARLES W. LOOMIS AND ARTHUR P. YATES, OF SYRACUSE, NEW YORK.

CHECK-REGISTER.

SPECIFICATION forming part of Letters Patent No. 244,465, dated July 19, 1881.

Application filed April 19, 1881. (No model.)

To all whom it may concern:

Be it known that we, CHARLES W. LOOMIS and ARTHUR P. YATES, of Syracuse, in the county of Onondaga, in the State of New York, have invented new and useful Improvements in Check-Registers, of which the following, taken in connection with the accompanying drawings, is a full, clear, and exact description.

10 This invention has reference to the registration of that class of checks which are used in restaurants and other places of business as a means of showing the cashier the amount to be collected from the patron.

15 The object of the invention is to provide a simple, convenient, and at the same time reliable means of keeping account of the number and amount of the checks issued to the customers and collected by the cashier each 20 day, or within a certain period; and to that end the invention consists in the hereinafter-described peculiar construction and combination of the registering mechanism and its in-closing-case, the operation of which requires 25 only one set of checks and the use of only one hand of the operator, as will be hereinafter more fully explained.

In the accompanying drawings, Figure 1 is a front view of our improved check-register; 30 Fig. 2, a vertical transverse section of the same. Fig. 3 is an enlarged isometric view of the registering mechanism detached from the case. Fig. 4 is a detail view of the gage employed in lieu of the graduations on the check-receptacle; and Fig. 5 is a transverse section of the 35 check specially adapted for our registering apparatus.

Similar letters of reference indicate corresponding parts.

40 A represents the case of the registering apparatus, composed of wood or other suitable material, and finished on its exterior in any desirable style. The upper portion of the case A, which constitutes the main portion thereof, 45 projects with its front over the lower portion of the case, and thus forms a recess, R, underneath the former. The bottom plate of the projecting portion is provided at or near the front edge with a forwardly and downwardly sloping aperture, D, which constitutes the delivery for the checks, as hereinafter explained. 50 Upon the top of the aforesaid bottom plate is

secured a guide, a, in the form of a horizontal plate, terminating with a downward deflection, f, which is fitted into the sloping aperture D, 55 and forms a chute for the checks carried to their said delivery from the case.

Over the guide a is mounted the receptacle for the checks to be registered. Said receptacle we prefer to make in the form of a vertical 60 cylindrical column or tube c, which has at its front a longitudinal slot, o, and a graduated scale, s, along the side of said slot, said graduation being made to correspond with the thickness of the checks used. The base of the 65 column c is above the guide a a distance equal to the thickness of one of said checks, and through the passage d thus formed slides a plate, b, guided by flanges on the sides of the guide a, before described. The slide b is allowed to move a sufficient distance rearward to carry its front end from under the interior of the column c, and thus allow the checks in 70 said column to settle down onto the bottom plate of the guide a. A forward movement of 75 the slide b forces the bottom check out from under the column and carries it to the chute f, from whence it drops out of the case A through the delivery D.

From the bottom of the slide b projects a 80 rigid pendent shank, g, to the lower extremity of which is connected a rod which is extended through the front of the lower and recessed portion of the case A, and provided at the exterior of the same with a suitable knob or handle, h, by means of which the slide b can be 85 operated. By connecting the slide b with the guide a by a tractile spring, S, and interposing between the shank g and inner face of the case A an expansive spring, r, the slide is held 90 normally in a retracted position, requiring only a pull on the knob h to cause the slide b to deliver the check through the aperture D, the slide b resuming its normal position automatically with the release of the knob h. 95

The delivery D being arranged directly over the knob h allows the operator to catch the check issuing from said delivery by the same hand with which he manipulates the knob, thus greatly facilitating the operation.

100 V represents a weighted follower applied to the top of the uppermost check in the column c, and having a pointer, w, extended through the slot o for the purpose of more definitely in-

dicating the number of checks drawn from the column.

The upper or main part of the case A is provided in front with a hinged drop leaf or lid, T, which, when opened, as indicated by dotted lines in Fig. 2 of the drawings, gives access to the tubes or column c for replacing the checks and for taking account of the registries, and at the same time forms a shelf or tablet upon which to place the account of the registries taken from the column c.

p denotes a gage in the form of a weighted follower, adapted to enter the column c, and having a graduated stem, t, which slides in the groove o, and by the coincidence of its graduations with the top of the column indicates the number of checks drawn from the base of the latter, said gage being more especially designed to be used in lieu of the graduations on the column when obliterated or defaced, or the column is made of wire or other material not admitting of the graduations e.

Since the arrangement of our registering apparatus makes it necessary that all the checks should be of a uniform thickness and perfectly true, we make our checks concave, as illustrated at E in Fig. 5 of the drawings, thereby preventing warping and buckling of the center of the check and the resultant variations in the height of a number of checks placed one upon another.

Having described our invention, what we claim as new, and desire to secure by Letters Patent, is—

1. The guide-plate a, provided at its front end with the chute f, the slide b, provided with the rigid pendent shank g, the forward-extended handle h, connected to said shank, and the graduated column c, mounted over the guide a, back of the chute f, in combination 35 with the case A, provided at its front end with the delivery D, and underneath the latter with the recess R, through the front plate of which the handle h protrudes, substantially as shown, and for the purpose set forth.

2. In combination with the case A, provided at its front with the delivery D and recess R underneath said delivery, the guide a, having the chute f adjacent to the delivery D, the graduated column c, arranged over the guide 40 a, with the passage d between them, the slide b, connected with the guide a by the spring s, the pendent shank g, projecting from the slide b, the forwardly-extended handle h, connected to the shank g and protruding at the front of 45 the recess R, and the spring r, interposed between the shank g and front of the case, all substantially as described and shown.

In testimony whereof we have hereunto signed our names and affixed our seals, in the presence of two attesting witnesses, at Syracuse, in the county of Onondaga, in the State of New York, this 15th day of April, 1881.

CHARLES W. LOOMIS. [L. S.]
ARTHUR P. YATES. [L. S.]
